UNITED STATES PATENT OFFICE.

TALLMADGE M. RICE, OF SPRINGFIELD, OHIO, ASSIGNOR TO WHITELEY,
FASSLER & KELLY, OF SAME PLACE.

AUTOMATIC GRAIN-BINDER.

SPECIFICATION forming part of Letters Patent No. 267,935, dated November 21, 1882.

Application filed April 21, 1880. (Model.)

To all whom it may concern:

Be it known that I, TALLMADGE M. RICE, of Springfield, Clarke county, State of Ohio, have invented new and useful Improvements in Automatic Grain-Binders; and I do hereby declare that the following is a full and exact description of the same.

My invention relates to a machine for automatically separating a gavel from a flowing stream of grain, compressing and binding the same, and discharging the bound bundle from the machine; and it consists in the peculiar gaveler or separator, the tension and take-up devices, and a cord-depressor on the binding-arm, as hereinafter described, and particularly pointed out in the claims.

That others may fully understand my invention, I will now particularly describe it, having reference to the accompanying drawings wherein—

Figure 1 is a transverse vertical section of my machine. Fig. 2 is an enlarged elevation of the cord-tension device. Fig. 3 represents the discharger. Fig. 4 is an enlarged elevation, showing the operation of the cord-carrier in placing the band upon the knotter. Fig. 5 is an enlarged elevation, showing the cord-guide and gate in position. Fig. 6 is an end and side elevation of the gate. Fig. 7 is a plan and longitudinal section of the end of the cord-carrier. Fig. 8 is an end elevation, showing the exterior gearing for operating the various parts.

A is the supporting frame-work of the machine. Grain is delivered to the receptacle B by an endless apron or other suitable device. Motion is transmitted from the prime mover to the main binder-shaft C by a chain-belt or shaft with gearing of any approved kind. From the main shaft C motion is communicated to the several operative devices by suitable gearing in train, and at the completion of the binding of each bundle the motion of the machine is arrested and held at rest until the accumulation of delivered grain is sufficient to form another proper-sized bundle, when the detent is automatically tripped and the binding machinery again set in motion.

At the end of the shaft C there is a bevel-pinion, D, which meshes with a similar bevel-pinion, E, upon the shaft of which there is also

a small spur-wheel, F. For convenience and compactness, the spur-wheel F is in the plane of the axis of the shaft C, and is mounted upon a stud, a, which is rigidly secured to a mounting-plate, b, upon which also the bearings of shaft C are placed. The pinion F meshes with and drives the main wheel G, from which all the groups of operative devices take their motion. One revolution of the wheel G completes the operation of separating, binding, and discharging one bundle.

The wheel G is provided with a peripheral flange on each side, which flanges are not continuous, and is armed also with projecting trips or cams, the uses of which wheel and appurtenances are to impart intermittent rotations to the pinions in mesh with said wheel, as hereinafter more particularly described.

The shaft C is provided with a clutch-sleeve, e, whereby it is coupled with the pinion E. (See Fig. 8.) A spring, f, tends to throw said clutch into engagement, and it is retracted and carried out of engagement by a lever, g, which at each revolution of the main wheel G is caught by a stud, h, on said wheel and pulled down until the clutch is retracted and liberated. To render this catch effective and sure, the outer end of the lever g is provided with a transverse orifice or socket, into which is fitted a bolt, i, the end of which forms a cup, and this cup receives and holds the stud h. When the lever g has been moved far enough to disengage the clutch e the wheel G and all the binding devices come to rest immediately. The bolt i may be withdrawn from its engagement with the stud h by a bell-crank lever, and the spring f immediately impels the clutch into engagement, and the binder is started again.

The clutch-withdrawing device is made in two parts capable of motion through different distances, so that the motion of the withdrawing-lever g may be greater than the motion of the clutch-sleeve without causing any disaster to the parts. These parts are, however, described and claimed in another specification filed, of even date herewith.

All of the gearing which actuates the several devices and groups of devices have their studs or bearings upon a single frame-plate, H, (see Fig. 8,) which is bolted to the front side or end frame of the binder, and serves to

hold the parts of said frame in place as well as to rigidly maintain in proper relative position all of said bearings, and thereby keep in proper connection the several related and co-acting parts.

Starting with the initial movement of the main wheel G, when the clutch e has gone into engagement the first pinion in mesh with said wheel G which is moved thereby is the pinion 10 J. This pinion is made long enough to span the spur-teeth of the wheel G and also the teeth of the pinion K. This is necessary because a part of the teeth in range with G are cut away to form a segment and permit J to 15 come to rest at each revolution, while with K, which is driven by J, the mesh must be continuous. At its back the pinion J is provided with a crescent-plate, p, which at the proper time rests upon the flange on the back of wheel 20 G and prevents the pinion J from revolving. The pinion J is also provided with a double and long tooth, o, which meshes with a corresponding recess in the pinion K. When in 25 position of rest the pinions J and K are in mesh with the long tooth o in its recess. The plate p is on the flange, with its front horn just coming in contact with the trip or stop on the wheel G, whereby the pinion J is set in motion. The point or horn of the plate p passes 30 down through one of the intervals in the flange to permit said revolution. As the initial movement of the pinion J is given by the point or horn of the crescent, it is slower than is due to the motion of wheel G, and the long tooth 35 o equalizes this by imparting to the pinion K a relatively more rapid motion, and it also serves as a guide in putting the gears together in the proper relation to each other. The pinion K is mounted on the end of a shaft, L, 40 the inner or rear end of which is supported in a bearing on the bridge-piece M, one end whereof is bolted to the inner cross-piece, N, of the binder-frame, and the other end is supported upon the shaft O, the ends whereof are in boxes 45 at the end frames of the machine.

The inner end of the shaft L bears a crank, q, whereby the separator P is actuated. The separator P is mounted upon the crank q at about the middle of its length. Its front or inner 50 end is pointed and curved downward, so as to enter the stream of grain and pass through it easily. Its rear or outer end is provided with a laterally-projecting stud at r, which slides in a long slot, s, in the bridge-piece M. The front 55 end or point of said separator therefore travels in an elliptical path or circuit. A slide traversing a rod or any other approved form of guide may be substituted for the slot s. The separator advances high above the stream of 60 grain, dips through it, separates the gavel, and moves it outward, and while standing in position to cover the path of the cord-arm the pinion J goes out of mesh with the wheel G, and the separator pauses until the bundle has 65 been bound and discharged. This position of the separator is shown in dotted lines in Fig. 1. The separator, in combination with its act-

uating mechanism, is described and claimed in another specification filed of even date here-with. During the time when the separator is 70 in action all the remainder of the apparatus is at rest; but when the separator has come to rest, then pinion Q goes into action. The point of this wheel's crescent-plate u at that moment encounters the starter t on the wheel G, 75 and is directed inward through the interval in the flange c, so that the pinion Q is permitted to revolve. The pinion Q is provided with a radial arm, v, and a stud, w, at the end of the same, and said stud rests in a curved slot, y, 80 in an arm, R. The arm R is mounted on the shaft S, which also carries the cord carrier and compressor T. The bearings of shaft S are at opposite extremities of the frame A. However, it is only required that the shaft O shall 85 extend entirely across the machine to avoid placing a box or bearing for it in a position where it would be exposed, and might also obstruct the movement of the bound bundle in being discharged. 90

The upper end or point of the cord-arm T is provided with an anti-friction roller to prevent the cord from cutting the arm. There is also, further back, a slot through said arm, and within said slot a dog, N', is pivoted. This 95 dog has a projecting head, n³. When the arm T comes up into position over the tyer and cutter the projecting lip or plate of the shield or cord-guides L' strike under the tail of the dog and cause the head to protrude downward to 100 strike and depress the cords between the neck of the cord-looping cylinder and the gripper and cutter E' to make more certain the proper seizure and severance of said cords. 105

The binding-cord may be taken from a spool 110 like the spool I, or from balls in a box, as preferred. From the spool or receptacle the cord passes through the guide-eye on the under side of the spring tension-plate R', and between 115 said tension and its stirrup s', so that it is subjected to the slight pressure of said spring. It then passes upward through an eye, g³, in the end of the tension-plate R', and thence through the eye of the spring take-up P', 120 which is secured to the under side of the binding-table and acts in a downward direction, and thereby draws the cord over the end of the tension-plate, and insures a strong tension with a weak spring, because the strain upon the cord forces the tension-plate R' down toward its stirrup, and correspondingly increases 125 its pressure upon the cord therein. The strain upon the cord will be variable, and the tension will therefore be correspondingly variable. The cord renders freely through the guide-eyes 130 as soon as the take-up is drawn up to the tension-plate. The tension and take-up devices require no change of adjustment to compensate for any change in the size or quality of the cord. They also permit the passage of 135 knots and bunches in the cord.

It has hereinbefore been stated that the grain is delivered to the receptacle B by any proper mechanism for that purpose. Said grain will

enter through the orifice or opening m'' in the inner side of the binder, and will fall upon the floor of the receptacle behind the plates or aprons S' , which are attached at their upper edges to the rock-shaft n^2 , which turns in bearings attached to the cross-piece N of the binder-frame.

A short arm, T' , is mounted loosely upon the end of the shaft n^2 , but its range of motion is limited by a head, p^2 , which is rigidly fixed to the end of said shaft, and is provided with shoulders projecting over the arm T' , so as to limit its movement. The range of movement of the arm T' indicates the movement of the apron S' before tripping the binder-gearing. The relative positions of the lever T' and the aprons S' at the time of tripping may be regulated by adjustment of the head p^2 , which may be effected by means of a set-screw or other suitable device.

The arm U' upon the shaft L assists the separator P in moving the separated bundle forward squarely to the binder and assists in separating the butts from the incoming grain.

25 Springs may be applied forward or back, as cases may require, of the springs a' , for the purpose of preventing one end of the grain from moving too far as it comes into the binding-receptacle, before it is bound.

30 On the inner side of the cord-guides L' there is a swinging gate, M' , which closes down upon the mouth of said cord-guides and aids in preventing the entrance of straw to the knotter. The cord-arm T pushes this gate upward as it passes over the tyer, and the cord is thereby confined in the grooved upper surface of the arm while in position above the tyer.

35 The gearing hereinbefore described for operating the various parts, together with the

clutch and tripping mechanism, the same being represented in Fig. 8, also the compressing and discharging arm $a' V$, also the knotting, holding, and cutting devices, form the subjects of other specifications filed by me, and are not herein claimed.

Having described my invention, what I claim as new is—

1. In an automatic binding-machine, a gaveler carried on the wrist of a crank while its rear end traverses a slotted guide, so as to have a circulatory movement at its front end from above the grain, descending into and through the stream of grain, and pausing therein by the path of the cord-carrier, to hold the gavel separate from said stream, combined with an independent cord carrying and compressing arm moving upward from below the receptacle in the path guarded by said gaveler, for the purpose set forth.

2. The cord-arm T and take-up spring P' , combined with the tension-plate R' and friction-loop s' , whereby the cord is compressed between said loop and plate by the action of said plate, modified in one direction by the action of the cord-arm when the cord is being drawn out and at all other times in the opposite direction by the action of the take-up, as set forth.

3. The arm T , provided with the pivoted dog N' , combined with the projecting lips of the shield L' , whereby said dog is pushed forward to depress the cords between the knotter and cutter, as set forth.

T. M. RICE.

In presence of—

E. H. BARNES,
A. N. SUMMERS.
